Primary Examiner — Elizabeth J Oswecki*Assistant Examiner* — Yelizaveta Y Masalimova(74) Attorney, Agent, or Firm — Armstrong Teasdale, LLP(57) CLAIM

The ornamental design for a slipper, as shown and described.

DESCRIPTION

FIG. 1 is a perspective view of a slipper showing my new design.

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines illustrate unclaimed subject matter and form no part of the claimed design.

1 Claim, 6 Drawing Sheets(56)
